UNITED STATES PATENT OFFICE.

GEORGE P. KLINE, OF MOLINE, ILLINOIS, ASSIGNOR TO WILLIAMS, WHITE & COMPANY, OF MOLINE, ILLINOIS.

METAL-PUNCHING MACHINE.

1,415,246.

Specification of Letters Patent. Patented May 9, 1922.

Application filed October 27, 1919. Serial No. 333,744.

To all whom it may concern:

Be it known that I, GEORGE P. KLINE, a citizen of the United States, residing at Moline, in the county of Rock Island and State of Illinois, have invented certain new and useful Improvements in Metal-Punching Machines, of which the following is a specification.

My invention has reference to metal punching machines, and more specially to that class of such devices which are known as multiple punches, wherein a plurality of the punching tools are supported and arranged in the machine so as to be operated in unison. As it is frequently necessary to change the position of the tools longitudinally of the supporting head or ram, it is essential that they should be held in place in such a manner that they can be readily loosened, for the purpose of adjustment, or completely detached, if desired. At the same time the mode of attachment of the tool holder to the operating head must be such as to enable such tool-holder to withstand all the strains consequent upon the punching operation, and especially the stripping strain which accompanies the upward movement of the head.

In former machines of this class it has been usual to connect the punch-holder with the operating face of the ram by means of bolts, two or more of such fastening devices being employed for that purpose, and in some cases only one bolt has been used, in connection with what is termed a detent, such detent having an engagement in a channel longitudinally of the ram. The bolts employed are frequently difficult of access, and require considerable labor and time for removal and replacement. Their use also calls for a specially constructed channel in the movable head, and extra bolt sustaining parts on the punch holder. One of the purposes of my invention is to do away with the use of bolts entirely, and connect the tool-holder with the operating face of the ram in such a way that it can be quickly and easily released therefrom. The manner of construction and means for attachment of the tool-holder also make it possible to greatly simplify the form thereof, without detracting from its efficiency.

Another requirement of a machine of the

class mentioned, is that all of the punches must be held in alignment longitudinally of the head, so as to coincide at all times with their several dies, and my device is particularly adapted for holding them firmly, against movement transversely of the head.

The invention is also constructed and arranged so that it can be quickly secured in place from that side of the machine most accessible to the operator. When attached, the punch-holder is entirely below the operating face of the movable head, instead of projecting upwardly along one or other of the side faces of such head, as is the case in some other punching machines.

In my device the punch-holder is readily slipped into position at its inner end, and is held therein by a clincher grip or lock, which holds the same rigidly against any movement transversely of the movable head, and eliminating the use of bolts or other attachments usually employed for that purpose. The opposite end of the tool-holder is connected with the head by movable attachments, which are secured to the holder in such a way that they cannot become disconnected and displaced, when not in use.

The above, and other features and advantages of my invention will more fully appear from the following specification, reference being had to the drawings accompanying the same, in which:

Fig. 1 shows my invention in side elevation, with a fractional part of the movable head of the machine shown in section.

Fig. 2 is a plan view of one of the punch-holder units.

Fig. 3 is a view, similar to Fig. 1, showing a modified construction of the device.

Figs. 4 and 5 are details of the cam member 25, in side elevation and edge view, respectively.

Fig. 6 shows a modified form of the tool-holder tongue.

There are illustrated in said drawings only such parts of the machine as are involved in the present application, similar structural parts being indicated therein by corresponding reference characters. There are portrayed in the drawings and set out in the specification herein, the preferred embodiment of the device, with some modified

forms which have occurred to the applicant, it being understood that he does not necessarily confine himself thereto, but that other changes in the form and arrangement of the parts thereof may be obvious to those skilled in the art to which this device belongs, without departing from the general scope and spirit of the invention.

1 represents a portion of what usually comprises the lower end of a movable ram, or cross-head, with which the punch-holders are connected, in spaced-apart relations, said head being provided at one of its sides with a downwardly projected extension 2, in one face of which is a longitudinal recess 3, the lower face 4 of which has a downward and inward inclination. In the usual arrangement and operation of such machines, the extension 2 would be located on the inner edge of the head 1, or farthest from the operator, with the recess 3 disposed toward the front of the machine.

A tool-holder 5 is provided with a socket 6, in which is held the upper part of a punch 7, at the upper end of which is a head 8, preventing movement of the tool downwardly in the holder. At one of the ends of the tool-holder is a tongue 9, the lower face of which conforms to the face 4 of the recess 3, when the tool-holder is in operative contact with the lower face of the head 1, as shown in Fig. 1. At the opposite side of the holder 5 is a pair of downwardly projected ears 10, supporting a pivot 11, upon which is swingingly mounted an arm 12, which passes upwardly through an opening 13 in the bottom plate of the part 5, and is provided at its upper end with a hook-like extension 14, adapted for engagement with a longitudinal rib 15 on the face of the head 1. The upper face 16 of the rib 15 is preferably disposed downwardly and inwardly similarly to the face 4 of the recess 3, said face 16 providing a supporting ledge for any desired number of the hook members 12. The extension 14 of said hook member is fitted with a set-screw 17, the end of which has a bearing against the face 16, and by the operation of which the engaging faces of the head 1 and punch-holder 5 can be drawn tightly together.

The tool-holder is applied to the head 1 by first securing the tongue 9 in the recess 3, which is accomplished by inclining the tool-holder and introducing the tongue into the recess, at the same time rocking the tool-holder forwardly into position, in engagement with the head 1. When the faces of the parts 1 and 5 are in contact the lower face of the tongue 9 is also in close engagement with the lower face 4 of the recess, making it impossible to remove said tongue laterally of the head, except by a reversal of the movement by means of which it was inserted in the recess. The engagement of said co-

acting faces of the tongue and recess is in effect a clincher grip, locking the tongue 9 from release, and holding the member 5 firmly from movement with relation to the head 1, transversely thereof. It will be obvious that movement of the tool-holder toward the inner face of the head 1 is equally impossible. A series of punches in which the tools have been properly aligned will be maintained in their positions when supported by tool-holders which are thus secured in place in the machine. When the part 12 of the tool-holder is connected with the rib 15, there is no possibility of the tool-holder becoming detached or moving out of its proper working position.

If it is desired to adjust the position of the tool-holder, this is accomplished by loosening the screw 17, sufficiently to permit a movement of the holder longitudinally of the head 1. To detach the same, the arm 12 is swung away from the head until it clears the ledge 16, when the tool-holder can be detached, in the manner hereinbefore set forth. In the operation of inserting the tongue 9, or removing the same, a little clearance is required for the inner end thereof, and this is provided by a channel 3^a in the lower face of the head 1, just above the recess 3. The face of the extension 2 which is adjacent to the tool-holder is also beveled, or otherwise cut away, as at 18, to permit free movement of the outer end of the tool-holder downwardly.

The tool-holder is provided with the usual gag-block 19, if desired, which is held normally between the head of the punch and the operating face of the head 1, such block being slidable in the tool-holder, and provided with a frame extension 20, on the outer end 105 of which is a handle 21. The arm 12 is permitted the necessary amount of movement within the frame 20, and such frame is also allowed the necessary sliding movement without interference from said arm.

In Fig. 3 is shown a modified form of the device, wherein the recess 3 is provided with a curved lower face 22, the lower face of the tongue 9 conforming thereto. As in the former construction, the tongue can be rolled into or out of position by rocking the tool-holder, and the tool-holder will be locked from release when held in close contact with the head 1. In this construction the tool-holder is shown with a pivot 23 fixed in the sides thereof, upon which is mounted an arm 24, having a bent upper end in which is pivoted an eccentric cam 25, adapted for engagement with the upper face of the rib 15, to hold the parts 1 and 5 tightly together, as shown in Fig. 3. It will be obvious that the release of such parts can be quickly effected by turning the handle 26 of the cam 25 outwardly, and dropping the outer end of the tool-holder downwardly. In this form

the side pieces of the frame 20 are provided with slots 27, to permit a sliding movement of said frame.

In Fig. 6 the tongue 9 is shown provided with a face 28, which is parallel with the lower face of the tongue, and which will permit the seating of said tongue in the recess 3 without cutting away any portion of the lower face of the head 1.

In the punching operation the force of the head 1 is directed downwardly through the gag-block 19 and punch 7, the punch-holder maintaining said parts in their proper relations, and preventing any movement thereof out of a direct line. In the return movement of the head 1, any tendency of the stress which results from stripping the work from the punches to detach the tool-holder from the head is overcome by the extension 9, firmly supported on the ledge 4 at one side of the line of action of the machine, and the swinging hook in engagement with the ledge 16 on the other side of said line of action.

It will be apparent that by reason of the swinging hook-members having a pivotal connection with the tool-holder, there is no possibility of such parts becoming lost or mislaid. Such parts could be also slidably mounted in the tool-holder, or otherwise mounted therein so as to be permitted the desired movement with relation to the head 1.

When the handle of the cam 25 is forced inwardly to a sufficient extent, it operates to lock the cam in engagement with the rib 15 against the accidental release thereof. The upper face of the rib 15 can also be made horizontal, if desired, or of other forms.

What I claim, and desire to secure, is:

1. In a device of the class described, a movable member having a recessed extension the lower side of the recess having a downward and inward inclination; a tool-holder provided with a tongue adapted for engagement with said recessed extension; and means for attachment of said tool-holder to said movable member, at a point other than said extension.

2. In a device of the class described, a movable member having a recessed extension on its operating face the lower side of the recess having a downward and inward inclination; a tool-holder with a tongue at one of its ends adapted to engage and lock in said recessed extension; and means at the other end of said tool-holder for the attachment thereof rigidly to the face of said movable member.

3. In a device of the class described, a movable member having an operating face adapted for the support of a tool-holder, and provided with a recessed extension the lower side of the recess having a downward and inward inclination; a tool-holder pro-

vided at one end with a tongue adapted for engagement with said recessed extension, and at the other end with a hook member, adapted for connection with said movable member.

4. In a device of the class described, a movable member adapted for the support of a tool-holder, and provided at one of its sides with an extension having a recess the lower side of which has a downward and inward inclination; and at the other side with a laterally projected rib; a tool-holder provided at one end with a tongue adapted to engage said recess and at the other with a hook adapted to engage said rib; and means carried by said hook for clamping said movable member and said tool-holder tightly together.

5. In a device of the class described, a movable member provided at one of its sides with a downwardly projected extension having a recess in its inner face, and at the other side with a lateral rib, the lower side of said recess being inclined downwardly and inwardly; a tool-holder provided at one of its ends with a tongue adapted for engagement with said recessed extension, and at the other end with a hook member adapted for engagement with said lateral rib; and means carried by said hook member for clamping a tool-holder rigidly against the operating face of the movable member.

6. In a device of the class described, a movable member adapted for the support of a tool-holder, having along one side of its operating face an extension provided with a longitudinal channel, the lower side of which is inclined downwardly and inwardly; and along the other edge with a laterally projected rib; a tool-holder provided with an extension capable of engagement with said channel by a rocking movement, and locked therein when the tool-holder is in operative contact with the face of said movable member; and a connecting member movably carried in the opposite end of the tool-holder from said extension, and adapted for engagement with said laterally projected rib.

7. In a device of the class described, a movable member adapted for the support of a tool-holder, provided at one of its sides with a recessed extension the lower side of the recess having a downward and inward inclination, and at the opposite side with a laterally projected rib, said recess and rib being provided with similarly disposed supporting ledges; a tool-holder provided at one end with a tongue adapted for engagement with said recess, so as to be held therein with a clincher grip, and at the opposite end with a movable hook member adapted for engagement with the ledge of said lateral rib, the engagement of said tongue and movable hook with said movable member op-

erating to hold said tool-holder in engagement with the working face of said movable member; and means for clamping said tool-holder and movable member in closed operative relation with each other.

8. In a device of the class described, a movable member adapted for the support of a tool-holder, provided at one of its sides with a recessed extension, and at its opposite side with a laterally projected rib, said recess and rib being provided with similarly disposed downwardly and inwardly inclined faces forming supporting ledges; a tool-holder provided at one end with a tongue adapted for engagement with the ledge of said extension, so as to be held therein with a clincher grip, and at its opposite end with a swinging member having a projection adapted for engagement with the ledge of said rib; the engagement of said tongue and swinging member operating to hold said tool-holder in approximate contact with said movable member; and means carried by said swinging member for clamping said tool-holder and movable member tightly together.

9. In a metal punching machine, a movable member designed for the support of a tool-holder, provided with longitudinal supporting ribs on opposite sides of the line of motion of the tool, having downwardly and inwardly inclined supporting faces; means for detachably connecting said tool-holder with one of said ribs; an outwardly curved hook member adapted for engagement with the other of said ribs; and a clamping device carried by said hook member, and adapted

for engagement with said last-named rib, to hold said movable member and tool-holder tightly together.

10. In a device of the class described, a movable member adapted for the support of a tool-holder, provided at one of its sides with a downwardly projected extension, recessed in its inner face, and at its opposite side with a supporting ledge, the lower side of the recess being downwardly and inwardly inclined; a tool-holder provided at one of its ends with means for engagement with said extension; a movable hook member at the opposite side of said tool-holder, adapted for engagement with said ledge; and a cam device carried by said hook member, also adapted for engagement with said ledge, to clamp said movable member and tool-holder tightly together.

11. In a metal punching machine, a movable member, adapted for the support of a tool-holder, provided at one of its lower edges with a downwardly projected extension having a detent channel in its inner face, the lower wall of which recess is inclined downwardly and inwardly, and at the opposite edge with a laterally disposed rib; a tool-holder having a detent extension for engagement with said channel; a hook member movably mounted in the opposite end of said tool-holder and adapted for engagement with said lateral rib; and a gag-block slidable in said tool-holder, said hook-member and gag-block having free operative movement with relation to each other.

In testimony whereof I affix my signature.
GEORGE P. KLINE.
